UNITED STATES PATENT OFFICE.

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA.

CAR ROOF.

Application filed November 19, 1924. Serial No. 750,840.

To all whom it may concern:

Be it known that I, CHARLES DAVID BONSALL, a citizen of the United States, and a resident of the city of Pittsburgh, in the 5 county of Allegheny and State of Pennsylvania, have invented a new and useful Improvement in Car Roofs, of which the following is a specification.

This invention relates principally to flexible car roofs of the kind wherein the metal roof sheets extend from eaves to eaves of the car between carlines and are loosely connected along their adjacent side margins by weatherproofing caps that are secured to the 10 substructure and thus serve to hold the roof sheets down on the car. The principal object of the present invention is to produce a roof of simple and economical construction that is easy of application and that will be 15 stiffer and stronger than previous roofs of the same weight and metal. The invention consists principally in increasing the strength and rigidity of the carlines by combining the carlines and weatherproofing caps 20 so that said caps cooperate with said carlines in carrying the roof load and resisting stresses; and it also consists in the construction and arrangements of parts hereinafter described and claimed.

30 In the accompanying drawing, wherein like symbols refer to like parts wherever they occur,

Fig. 1 is a plan view of a portion of the car roof embodying my invention;

35 Fig. 2 is an enlarged transverse section through one-half of the roof on the line 2—2 in Fig. 1;

Fig. 3 is an enlarged cross-section through one of the seams or joints adjacent to the 40 ridge on the line 3—3 in Fig. 2;

Fig. 4 is a similar cross-section adjacent to the eaves on the line 4—4 in Fig. 2;

Fig. 5 is a fragmentary section through the side plate of a modified roof construction, showing the adjacent portion of the roof sheet in elevation and the end portion of the carline in elevation; and

50 Fig. 6 is a cross-section through said carline and the portions of the sheets adjacent thereto.

The present roof comprises Z-bar side plates 5 that are connected by carlines 6 of substantially inverted channel-shaped section with outwardly projecting lateral base

flanges 7 at the bottom of their side walls. 55 The Z-bar side plates 5 are preferably arranged with their webs vertical and with their top flanges extending inwardly horizontally; and the eaves end portions of the carlines rest flatwise on the inwardly projecting flanges of the side plates and have their base flanges rigidly secured thereto by rivets 8.

Roof sheets 9 extend from eaves to eaves between carlines and are supported at their 60 eaves ends on wooden filler strips 10. Said strips extend from carline to carline and are secured to the top flanges of the side plates by bolts 11. The roof sheets are supported between the ridge and eaves by means of 65 purlins 12 which extend longitudinally of the car beneath the carlines and are bolted thereto. The roof sheets are also supported at the ridge by a ridge pole 13, which also passes beneath the carlines and is bolted 70 thereto. The roof sheets are supported on the filler strips, purlins, and the ridge pole above the plane of the lateral base flanges 75 of the carlines and have upwardly offset side marginal portions 14 that are inclined 80 upwardly and terminate in upstanding side marginal flanges 15 that extend from end to end of the sheets. The roof sheets are also provided at their eaves ends with depending flanges 16 which overhang the webs of the 85 side plates and terminate in inturned portions 17 that are spaced away from the webs of the side plates.

Weatherproofing members in the form of inverted channel-shaped seam covers A 90 straddle the upstanding side marginal flanges 15 of adjacent roof sheets, the inside width of said seam covers being sufficient to leave a space between each side wall thereof and said adjacent side marginal 95 flanges. The webs 18 of the channel-shaped seam caps A bear flatwise against the webs of the channel-shaped carlines and are riveted or otherwise rigidly secured thereto. The channel-shaped seam covers are provided along their lower edges with outwardly projecting lateral base flanges 19 100 that conform to the slope of the upwardly offset side marginal portions 14 of the roof sheets and are arranged to rest or bear flatwise on said portions, thereby holding the sheets down on the car. The eaves end portions of the seam caps are provided with

depending eaves flanges 20 which overlap the open ends of the carlines and the eaves corners of adjacent sheets and terminate in inturned portions 21 that are spaced away from the end flanges of the roof sheets.

By the arrangement described, the seam covers not only form a watertight seam or joint between adjacent roof sheets, but also serve to hold the sheet down on the car, 10 while permitting said sheets to accommodate themselves to the distortion of the roof by sluing thereon. It is particularly noted that the seam caps are rigidly secured flatwise to the tops of the carlines and thus 15 function not only as weatherproofing members; but also as load carrying members which cooperate with the carlines to increase their load carrying capacity and to resist any stresses that tend to twist them out of 20 shape.

The transverse seam caps A shown in the drawing are preferably made in three sections: namely, duplicate end members or 25 sections 22, which extend from eaves to points adjacent to the ridge, and a single intermediate or ridge section 23, which overlaps the ridge end portions of the two end sections for a suitable distance on each side of the ridge. The ridge section 23 of each 30 seam cap is preferably pressed outwardly adjacent to each end, as at 24, in directions crosswise thereof to provide space between the overlapping portions of the ridge and end sections for strips of tar paper or other 35 suitable material 25, which is dipped in paint before application. This arrangement provides a watertight joint between the overlapping ends of the cap sections well 40 adapted to prevent the entering of water into the car.

Running boards 26 extend longitudinally of the car at the ridge and are supported on the lateral top flanges of Z-bar running board saddles 27 whose lateral base flanges 45 rest on the ridge members 23 of the seam caps and are rigidly secured to said members by the rivets 28 that secure the ridge portion of the caps to the carlines.

It is noted that by reason of the seam or 50 carline cap being made in three sections the same cap sections are applicable to cars of different widths, and that the three thicknesses of metal formed by the base flanges of the running board saddles and the overlapping portions of the cap sections serve 55 to strengthen the cap and carline in the region of the ridge.

At points adjacent to the eaves, where the 58 seam caps are rigidly secured to the carlines by the rivets 29, the seam caps are provided with upstanding circular bosses 30 that serve to prevent water from entering the car through the rivet holes. Mashing of these 65 bosses during the operation of driving the rivets 29 is prevented by washers 31 which

receive the rivets and are of thickness sufficient to fill the space between the bossed portions of the caps and the tops of the carlines. These washers are provided with downwardly projecting thimble portions or 70 ferrules 32, which fit the rivet holes in the carlines and serve to retain the washers in place while the caps are being placed in position.

In the modified construction illustrated in 75 Figs. 5 and 6, each of the carlines comprises an upper member 30^a and a lower member 31^a riveted or otherwise rigidly fastened together with their side edge portions spaced apart approximately the thickness of a roof sheet throughout their length. Throughout the greater portion of its length, the greater portion of the form of the lower member 80 31^a is that of an inverted channel with wide horizontal flanges 32^a along its lower edges; but the end portions 33 of said lower member are first bent downwardly and then outward horizontally so that the lower flanges of said lower carline member will rest flatwise on the top of the side plate, to which 85 they are secured by vertical rivets 34. Preferably the side plate 35 is of Z-section with its top flange 36 extending inwardly horizontally and preferably the lower member 90 31^a of the carline does not extend beyond the vertical web 37 of the side plates.

Throughout the greater portion of its length, the upper member 30^a of the carline is also of inverted channel shape with wide horizontal flanges 39 at its lower side edges; but the end portions 40 of said upper member are bent downwardly beyond the vertical planes of the vertical webs 37 of the side plates but within the vertical planes of the outer edges of the horizontal flanges 41 of 100 said side plates; and the endmost portions of said lateral flanges of the downturned portions of said upper carline member are offset inwardly (as at 42) and riveted flatwise against said vertical web of the side plate.

By this arrangement, a space is provided between the web 37 of the side plate and the downturned portion 40 of said upper member sufficient to receive the end flanges 43 of the roof sheets 44 and permit play 105 thereof. The upper and lower members of the carline are so proportioned that, when the upper member is superposed on the lower with their flat web portions in contact, the horizontal flanges of the upper member 110 are spaced from the horizontal flanges of the lower member a distance substantially equal to the thickness of the roof sheet; and so that the spaces between the vertical legs 115 of the channels will not only receive the upturned flanges of the roof sheets but will permit said flanges to play to a reasonable extent back and forth between said vertical legs.

As stated above, the roof sheets extend 120

from side plate to side plate and have their ends flanged downwardly beyond the vertical webs of the side plates. In the normal position of the roof sheet, the downturned end thereof is spaced outwardly a sufficient distance beyond the vertical web of the side plate and a sufficient distance inwardly from the downturned ends of the upper member of the carline to permit the roof sheet to accommodate itself to the distortions of the roof by sluing thereon. In such sluing movement, two diagonally opposite corners of the roof sheet tend to move outwardly or away from the side plates, while the other two diagonally opposite corners tend to move toward the side plates, these movements being incidental to the sliding of the opposite side margins of the roof sheets in opposite directions endwise of the carlines adjacent to said edges respectively.

Among the advantages of the present construction are the great simplicity of the roof sheets and their freedom from severe stresses: also the cheapness and simplicity of the construction of the carlines, their great strength for a given amount of metal, and the facility with which they adapt themselves to the application of the roof. It is particularly noted that the downward deflection of the end portions of the lower member of the carline serves to introduce a truss action that greatly increases the capacity of the carline for carrying vertical load; and it is also noted that the cross-section of the carline is such as to afford it great strength for resisting other stresses to which the carline is subject in practice.

Obviously, the hereinbefore described arrangement admits of considerable modification without departing from the invention;

therefore I do not wish to be limited to the precise arrangement shown and described.

What I claim is:

1. A car roof comprising side plates, carlines of inverted channel-shaped section extending from side plate to side plate, roof sheets extending from side plate to side plate between carlines, metal caps of inverted channel-shaped section extending from side plate to side plate, said caps straddling said carlines and the adjacent side marginal portions of said roof sheets, the web portions of said carlines and caps being rigidly riveted together flatwise at points a substantial distance inwardly from the side plates and at points near the sides of the running board whereby said caps cooperate with said carlines in taking care of the carline stresses. 45 50 55

2. A car roof comprising side plates, carlines of inverted channel-shaped section extending from side plate to side plate, roof sheets extending from side plate to side plate between carlines and having upturned flanges at the sides thereof, and caps of inverted channel-shaped section straddling the carlines and the side marginal portions of adjacent sheets, each of said caps extending from side plate to side plate and consisting of a plurality of sections arranged end to end in overlapped relation with their web 60 65 70 portions riveted flatwise to the webs of the carlines at points inwardly from the side plates and at points near the sides of the running board, whereby said caps cooperate with said carlines in taking care of the 75 stresses to which said carlines are subject.

Signed at New Kensington, Pa. this 14th day of Nov., 1924.

CHARLES DAVID BONSALL.
